UNITED STATES PATENT OFFICE.

ERNEST J. JONES, OF BALTIMORE, MARYLAND.

HAME-FASTENER.

1,032,411.

Specification of Letters Patent. Patented July 16, 1912.

Application filed September 11, 1911. Serial No. 648,689.

To all whom it may concern:

Be it known that I, ERNEST J. JONES, a citizen of the United States, residing at Baltimore, in the State of Maryland, have 5 invented certain new and useful Improvements in Hame-Fasteners, of which the following is a specification.

My invention relates to improvements in hame-fasteners, and more particularly to 10 improvements in my Patent No. 958,253, dated May 17, 1910.

In actual practice, when the device embodied in my former patent is applied to double teams, I have found that the pivotal 15 bail, which constitutes the means for fastening the snap hook and the lever together, is frequently engaged by the breast-chain and constrained over the outer end of said lever, whereupon the latter is free to gravitate and result in a separation of the connections, and thereby defeating the very 20 object for which this particular construction was devised.

It is therefore, the purpose of my present 25 invention to obviate this inherent disadvantage by providing a fastening means which will positively inhibit any accidental disorganization of the hame-fastener.

To the accomplishment of the recited objects and others coördinate therewith, the 30 preferred embodiment of my invention resides in that construction and arrangement of parts hereinafter described, illustrated in the accompanying drawings, and embodied within the scope of the appended 35 claim.

In said drawings:—Figure 1 is a side elevation of the hame-fastener embodying my invention, and Fig. 2 is a similar view showing the lever disconnected from its companion snap-hook.

Similar reference characters indicate corresponding parts throughout the views.

As in the case of my former patent, the 45 invention comprises snap-hook members 1 and 2, and a lever 3, the member 1 being provided with a rack 4 and the member 2 and lever 3 being pivotally connected at 5, and otherwise arranged so that the trunnions 6 carried by the lever may be suitably 50 adjusted in said rack.

The improvement resides in rabbeting the outer curvilinear terminal of the snap-hook member 2, as at 7, forming a depending projection 8 on the end of the rabbeted portion, and constructing the outer proximal

end of the lever 3 with an aperture 9, to permit the projection 8 to extend therethrough. A lug 10 is fashioned on the end of the lever and extends laterally in the 60 same plane as the projection 8. Both the lug and projection have transverse openings 11 and 12, respectively, connected by a chain 13, the latter being permanently secured to the lug 10 and detachably fastened 65 to the projection 8 by the hook 14.

As exhibited in Fig. 1 of the drawings, the hame-fastener is in the position that it would assume when applied to the ends of a pair of hames, with the outer terminal of 70 the lever 3 resting flush contiguous the rabbeted portion 7 of the snap-hook member 2, and the projection 8 extending therethrough and fastened by the hook 14. When it is desired to disconnect these 75 elements, the hook 14 is withdrawn from the projection 12, whence the snap-hook and lever can be easily separated, as will be readily seen upon inspection of Fig. 2.

With this fastening means in operation, 80 all possibility of the same becoming disengaged by the breast-chain is precluded. Furthermore, if the outer curved terminal of the lever 3 should have any tendency to slightly oscillate from its relative flush position with the snap-hook 2, that portion of the lever on either side of the aperture 9 will impinge against the hook 14 and hold it securely against the wall of the opening 11 in the projection 8. 90

It should be understood that in its broader aspects my invention comprehends the employment not only of the means described, but of equivalent means for performing the recited functions. While the 95 arrangement shown is thought, at the present time, to be preferable, it is desired to reserve the right to effect such modifications and variations thereof as may come fairly within the scope of the appended claim. 100

What I claim is:—

In a hame-fastener, the combination of a pair of snap-hooks, a lever pivoted to one of said snap-hooks, means for adjusting the lever and the other snap-hook, said first 105 mentioned snap-hook having its outer terminal cut away, an apertured projection formed integral with and extending from the extreme end of said cut away portion, the outer end of said lever being curved and 110 adapted to fit in said cut away portion and lie flush with the outer edges and top sur-

face of said first mentioned snap-hook, said lever further having an outwardly extending integral projection on its extreme outer end and an opening on the inner side of and immediately adjacent said projection, said first mentioned projection being designed to extend through said opening, and a flexible connection having one end permanently secured to the second mentioned projection

and its other end adapted for detachable 10 engagement with the aperture of the first mentioned projection.

In testimony whereof I hereunto affix my signature in presence of two witnesses.

ERNEST J. JONES.
